(57) **CLAIM**

The ornamental design for a rider simulation apparatus, as shown and described.

DESCRIPTION

FIG. 1 is a rear perspective view of a rider simulation apparatus showing my new design;
FIG. 2 is a rear view of the rider simulation apparatus;
FIG. 3 is a front view of the rider simulation apparatus;
FIG. 4 is a right side view of the rider simulation apparatus;
FIG. 5 is a left side view of the rider simulation apparatus;
FIG. 6 is a top view of the rider simulation apparatus;
FIG. 7 is a bottom view of the rider simulation apparatus; and,
FIG. 8 is a perspective view of the rider simulation apparatus. The broken lines of the Figures illustrate environmental structure and portions of the rider simulation apparatus which form no part of the claimed design.
